(57) **CLAIM**

The ornamental design for a simulated stone architectural trim assembly, as shown and described.

DESCRIPTION

The claimed simulated stone architectural trim assembly is used to surround an electrical junction box and can be mounted on an exterior or interior surface.

FIG. 1 is a top plan view of one embodiment of a simulated stone architectural trim assembly showing our new design; FIG. 2 is a front elevational view of the design of FIG. 1; FIG. 3 is a side elevational view of the design of FIG. 1; FIG. 4 is a cross-sectional view taken along the line 4—4 in FIG. 1;

FIG. 5 is a cross-sectional view taken along the line 5—5 in FIG. 1;

FIG. 6 is a top plan view of another embodiment of a simulated stone architectural trim assembly showing our new design;

FIG. 7 is a front elevational view of the design of FIG. 6; FIG. 8 is a side elevational view of the design of FIG. 6; FIG. 9 is a cross-sectional view taken along the line 9—9 in FIG. 6; and, FIG. 10 is a cross-sectional view taken along the line 10—10 in FIG. 6.

The rear of the simulated stone architectural trim assembly forms no part of the claimed design.
